ATTY'S.

UNITED STATES PATENT OFFICE.

WILLIAM J. PARSONS, OF MONTAGUE, MASSACHUSETTS, ASSIGNOR TO MILLERS FALLS COMPANY, OF MILLERS FALLS, MASSACHUSETTS, A CORPORATION OF MASSACHUSETTS.

SPRING-MANIPULATING TOOL.

1,235,237.

Specification of Letters Patent.

Patented July 31, 1917.

Application filed March 27, 1917. Serial No. 157,788.

To all whom it may concern:

Be it known that I, WILLIAM J. PARSONS, a citizen of the United States, residing at Montague, in the county of Franklin and 5 State of Massachusetts, have invented new and useful Improvements in Spring-Manipulating Tools, of which the following is a specification.

This invention relates to tools for engaging helical springs, such as the valve springs of automobile and motor boat engines, and manipulating such springs in such manner as to render them temporarily inoperative and permit the removal of the valves when 15 it becomes necessary to grind the same.

The invention is embodied in the improvements which I will now proceed to describe and claim.

Of the accompanying drawings forming 20 a part of this specification,—

Figure 1 is a side view of a tool embodying the invention, adapted to engage one end of a spring and lift the same from an abutment.

25 Fig. 1^a is a fragmentary view illustrating the operation of the tool when the same is adapted for operation as shown by Fig. 1.

Fig. 2 is an edge view of the tool.

Fig. 3 is a view similar to Fig. 1, showing the tool adapted to engage opposite end portions of a spring to longitudinally compress the same.

Fig. 4 is an edge view of the part herein-after called the guide.

35 Fig. 5 is an edge view of the part herein-after called the holder.

The same reference characters indicate the same parts in all the figures.

In the drawings, 12, 12 designate a pair 40 of elongated stiff metal arms, each of which is provided at its outer end with a jaw 13 formed to engage a spring 14, said jaws being preferably formed by flattening and bifurcating the outer ends of the arms, as 45 shown by Fig. 2. As shown by Fig. 1^a one of the jaws may engage a fixed abutment 15, while the other jaw engages an end convolution of the spring, so that when the jaws are moved apart the engaged end of the 50 spring is lifted relatively to the abutment 15.

As shown by Fig. 3, the jaws may be engaged with the convolutions at opposite end portions of the spring, so that when the

jaws are moved toward each other, the spring will be longitudinally compressed 55 with its major portion between the jaws.

Each arm is provided with two faces 16 and 17, said faces being parallel with each other and inclined relatively to the jaw 13.

The inner ends of the arms 12 are connected by pivots 18 with opposite ends of a holder which is preferably of sectional construction for the purpose hereinafter described, the holder including a central section 19 having oppositely projecting pivot 60 studs 20 and end sections 21, socketed to receive and turn on the studs 20, the end sections being therefore swiveled to the central section. The end sections 20 are provided with slots 21^a receiving the inner ends 70 of the arms 12, the arrangement being such that the said arms swing in the same plane and are movable simultaneously in opposite directions.

22 designates a guide, which is preferably 75 an elongated bar having slots 23 through which the arms 12 pass loosely, each slot being provided with an outer guide member 24 and an inner guide member 25, said members being preferably circular studs extending 80 across the slots 23. The outer members 24 are removable to permit the arms to be inserted in and removed from said slots, each member 24 having a threaded portion engaging a tapped socket in the guide 22, 85 and a head 26, whereby it may be rotated.

I have provided manually operable means whereby the said holder and guide may be moved relatively to each other to vary the distance between them, said means being 90 preferably embodied in an operating screw 27 engaged with a tapped socket 28 in the holder, and having an unthreaded portion 27^a journaled in the guide. The rotation of the screw 27 causes relative movements of 95 the holder and guide, as indicated in full and dotted lines in Fig. 1.

When the tool is adapted for use, as shown by Figs. 1 and 1^a, the inclined faces 16 of the arms bear on the inner guide members 100 25 and are separated from the outer guide members 24, so that when the distance between the holder and guide is increased, the inclined faces 16 and guide members 25 coöperate in swinging the arms simultaneously outward or away from each other,

as indicated by dotted lines, thus causing the arms to lift one end of the spring 14, as indicated by Fig. 1^a.

To adapt the tool for use as shown by Fig. 3, the outer guide members 24 are removed, the arms 12 are swung outwardly from the slots 23, and the end sections 21 of the holder are given a half rotation, after which the arms are again swung into the slots 23, their inclined faces 16 then facing outwardly and being adapted to bear on and coöperate with the outer guide members 24. When the holder and guide are relatively moved to increase the distance between them, the jaws 13 are moved simultaneously inward, or toward each other, and caused to compress the spring 14 from both ends.

I claim:

20 A spring-manipulating tool comprising a pair of elongated arms having jaws at their outer ends formed to engage spring conve-

lutions and inner and outer faces which are inclined relatively to said jaws, a holder to which the inner ends of the arms are pivoted 25 to swing in the same plane, said holder including a central section and end sections pivoted to said arms and swiveled to the central section to permit a rotative adjustment of the arms, a guide having a pair of 30 outer guiding members arranged to coöperate with two of the inclined faces on the arms in swinging the arms inwardly, and a pair of inner guiding members arranged to coöperate with the other inclined faces 35 on the arms in swinging the arms outwardly, and manually operable means for moving said holder and guide relatively to each other to cause the coöperation of said guide and inclined faces. 40

In testimony whereof I have affixed my signature.

WILLIAM J. PARSONS.
